UNITED STATES PATENT OFFICE.

DAVID A. MIDGLEY, OF SALT LAKE CITY, UTAH.

COMBINED RECEIVER AND DAMPER-REGULATOR.

No. 896,561.

Specification of Letters Patent. Patented Aug. 18, 1908.

Application filed January 25, 1908. Serial No. 412,627.

To all whom it may concern:

Be it known that I, DAVID A. MIDGLEY, a citizen of the United States, residing at Salt Lake City, in the county of Salt Lake and 5 State of Utah, have invented certain new and useful Improvements in a Combined Receiver and Damper-Regulator, of which the following is a specification.

This invention relates to combined receivers and damper regulators associated with steam heating apparatus, and has for its object to improve the construction and increase the efficiency and utility of devices of this character.

15 With these and other objects in view, the invention consists in certain novel features of construction, as hereafter shown and described and specifically pointed out in the claims, and in the drawings illustrative of the 20 embodiment of the preferred form of the invention, Figure 1 is a sectional elevation. Fig. 2 is a longitudinal section on the line 2—2 of Fig. 1 looking inwardly in the direction of the arrow. Fig. 3 is a transverse section on the line 3—3 of Fig. 1. Fig. 4 is a 25 diagrammatic view on a reduced scale showing the improved device arranged in connection with a conventional steam heating plant, including the generator and two of the radiators.

In Fig. 4 of the drawings is shown a conventional generator 10 having a smoke stack 11, two radiators indicated at 12 with the return pipes 13 leading therefrom, these parts 35 being of usual form.

The improved device is located between the radiators and the generator, at any convenient point, preferably near the generator, as indicated, and consists in a casing 14, 40 preferably elongated and divided by an intermediate partition 15 into two compartments 16—17, the compartments 16 being preferably larger than the compartment 17.

The partition 15 is provided at its lower end 45 with a transverse aperture 18, providing communication between the two compartments, and leading from the casing 14 is a discharge pipe 19, preferably arranged centrally of the casing and beneath the partition 15, so that 50 water will flow from both compartments into the discharge.

The casing 14 is provided with a cover 20, preferably bolted thereto, as at 21, so that it can be easily removed. The cover 20 is provided 55 with a sleeve 22 having a valve seat 23 and opening into the compartment 16, while

a similar sleeve 24 is arranged in the cover 20 and communicating with the compartment 17 and having a valve seat 25. A rod 26 extends through the sleeve 22 and terminates in a float 27 preferably weighted, as indicated at 28. Attached to the upper end of the rod 26 above the cover 20 is a chain 29, leading over suitable guide pulleys 30 and connected to the damper 31 of the generator 10, so that the rising and falling of the float 27 will effect the opening and closing of the damper 31, as hereafter explained. The rod 26 is also provided with a valve 41, preferably near the float 27, and adapted to engage the seat 23 when the rod is elevated to a sufficient extent as hereafter explained.

Connected to the outer end of the sleeve 24 is an elbow 32 from which an air pipe 33 leads into the smoke stack 11, or other convenient point.

The sleeve 24 is provided with a guide "spider" or similar device 34, through which a rod 35 is slidably disposed and extending into the compartment 17, and provided at 80 its lower end with a float 36, and at an intermediate point, preferably near the valve seat 25, with a valve 37 adapted to engage the seat 25 when the rod 35 and its float are elevated to a sufficient extent.

A water gage 38 is connected to the casing 14 and communicating with the compartment 16, and arranged upon the casing 14 opposite the gage 38 are indicator lines 39, to denote the air pressure in the casing. 90 The returns 13 from the radiators are united into a pipe 40 leading into the compartment 17 near its upper end, as shown. By this arrangement it will be obvious that when the float 36 in the chamber 17 is under a low 95 pressure, preferably about one ounce, the valve 37 will close against the seat 25 and shut off the flow through the elbow 32 and its pipe 33.

The float 27 in the compartment 16 is designed to regulate the ounces of pressure carried in the system, and can be raised and fastened to any desired point upon the chain 29 to correspond to any required number of ounces of pressure desired, and the damper 105 will be closed at this predetermined pressure, and the corresponding check draft opened.

When the pressure of water in the compartment 16 is sufficient to raise the float 27, the valve 41 on the rod 26 closes the opening 110 at the top of the compartment 16, which "seals" the entire system, thereby enabling

the operator to carry any desired amount of pressure of steam without the loss of any of the steam.

The partition 15 between the compartments "seals" the steam connection between the two compartments, and thus preventing the steam from passing from one compartment to the other.

Having thus described the nature of the invention, what is claimed as new is:—

1. In a steam heating apparatus including a generator having a controlling damper and a plurality of radiators, of a receiver divided into compartments each having an air outlet, means for conducting the return water from the radiators into one of said compartments, means for returning the water from the receiver to the generator of the system, a float in said return water compartment and arranged to actuate a valve to close the outlet therefrom when the water causes said float to rise to a certain predetermined level, a float in the other compartment, means for connecting said last mentioned float with the damper of the generator, and a valve associated with said last mentioned float and adapted to close the outlet from the said last mentioned compartment when the water causes the float thereof to rise to a certain predetermined level.

2. In a steam heating system, a single receiver divided into two compartments with an outlet from each and a pipe adapted to conduct the water from the receiver to the generator of the system, a float in each of said compartments, a valve associated with each of said floats and operative to close the outlets thereof when the water rises to a certain predetermined level, connecting means between the float of one of said compartments and the damper of said generator, and means for conducting the return water from the radiators to the other of said compartments, the return water having an unrestricted passage into the receiver.

3. In a steam heating system, a receiver divided into two compartments with an outlet from each and with a pipe adapted to conduct the water from the receiver to the generator of the system, a float in each of said compartments, a valve arranged to be operated by one of said floats to close the outlet to one of said compartments when the water rises a relatively short distance, and a valve arranged to be operated by the other of said floats to close the outlet to the other of said compartments when the water rises a relatively long distance, connecting means between the float and one of said compartments and the damper of said generator, and means

for conducting the return water from the radiators to the other of said compartments, the return water having an unrestricted passage into the receiver.

4. In a steam heating system, a receiver divided into two compartments with an outlet from each and a pipe adapted to conduct the water from the receiver to the generator of the system, a float in each of said compartments, a valve associated with each of said floats and operative to close the outlets thereof when the water rises to a certain predetermined level, connecting means between the float of one of said compartments and the damper of said generator, means for conducting the return water from the radiators to the other of said compartments, the return water having unrestricted passage into the receiver a water gage connected to said receiver, and spaced graduations associated with said water gage.

5. In a steam heating system, a receiver having a partition off from its center dividing it into two compartments with an outlet from each and with a pipe adapted to conduct the water from the receiver to the generator of the system, means for conducting the return water into one of said compartments, means for closing the outlet to said return receiving compartment when the water rises a relatively short distance, means for closing the outlet of the other compartment when the water rises a relatively long distance, and connecting means between said last mentioned outlet closing means and the damper of the generator of the system.

6. In a steam heating system, a receiver having a partition off from its center dividing it into two compartments with an outlet from each and a pipe adapted to conduct the water from the receiver to the generator of the system, a float in each of said compartments, a valve associated with each of said floats and operable to close the outlets of the compartments when the water rises to a certain predetermined level, the valve of one float being spaced a greater distance from its float than the spaced relation of the other valve with its corresponding float, connecting means between the float of one of said compartments and the damper of said generator, and means for conducting the return water from the radiators to the other of said compartments.

In testimony whereof I affix my signature, in presence of two witnesses.

DAVID A. MIDGLEY.
